United States Patent Office.

WILLIAM E. GEORGE, OF WRENTHAM, MASSACHUSETTS.

Letters Patent No. 79,338, dated June 30, 1868.

IMPROVEMENT IN MACHINES FOR PRESSING HATS.

The Schedule referred to in these Letters Patent and making part of the same.

TO ALL PERSONS TO WHOM THESE PRESENTS MAY COME:

Be it known that I, WILLIAM E. GEORGE, of Wrentham, in the county of Norfolk, and State of Massachusetts, have invented an Improved Machine for Pressing Hats; and do hereby declare the same to be fully described in the following specification, and represented in the accompanying drawings, of which—

Figures 1 and 2 are end views,

Figure 3 a longitudinal section, and

Figure 4 a cross-section or front-view of the female die and its fastenings.

The machine hereinafter described, is analogous to those which are the subjects of the patents, No. 20,837, granted July 6, 1858, to Hiram C. West, and No. 53,088, granted, March 6, 1866, to Monroe and A. H. Morse, assignees of Monroe Morse; that is to say, my machine involves the main principles of the patented machines, and contains new, valuable, and important features or improvements, by which certain parts of the machine and a series of moulds and dies are rendered capable of performing the work of several of the machines, as heretofore constructed and used. This will be more clearly understood from the following description of my improved machine.

In the drawings, A denotes the flexible or elastic die, and B the mould or female die. C is the steam-chest, hollow head, or vessel to receive steam, for the purpose of heating the mould. This vessel is formed with a flange, α , extending around it at its open end. This flange projects from the outer curved surface of the vessel, and rearward, and is concentric with an annular recess, δ , in which is placed a packing-ring, e , of vulcanized India rubber or other proper material.

The mould B is constructed with a flange, d , to extend from and around it, and rest against such packing. From this flange sundry projections e, e, e , extend in manner and at equal distances apart, as represented in Figure 5, which is a front view of the mould. These projections are to enter corresponding notches fff , made in the side of a clamp-ring, E, which encompasses the flange α of the head or heater C, and laps over the inner end thereof, in manner as represented.

A male screw, g , is cut on the periphery of the clamp-ring, so as to screw into an annulus, F, which also encircles the flange α , and extends down, and rests against its rear side, in manner as shown in the drawings.

A ring, h , having a diameter larger than that of the annulus F, is arranged concentrically therewith, and affixed to it by arms i, i, i . By laying hold of and turning the hand-ring h around, the screw annulus F will be revolved on the clamp-ring E, and will draw it against the flange of the mould, and set the same closely against the packing of the mould, so as to make a steam-tight joint.

In the machine of the said Morse, the flexible or elastic presser, and its flexible or elastic diaphragm, are fixed by a series of bolts and nuts directly to the head or part which supports the sectors and their operative mechanism, many bolts being requisite to make a tight joint near the circumference of the diaphragm. This renders the separation of the presser or elastic die from the head a matter of much labor and time; and as machines have been made and used heretofore, that is, before the date of my invention, the presser or elastic die has been allowed to remain fixed to its head, only one such die being used with the head. In carrying out my improvement, I fasten the diaphragm k and the elastic covering l of the die, directly to a flanged annular socket-piece, m , separate from the head G, which supports the series of sectors n, n , and the screw o , by which they are operated or moved.

Figure 6 is a front view,

Figure 7 an edge view, and

Figure 8 a rear elevation of the die as attached to the socket-piece m , which has a circular opening, p , to enable the sectors to come in contact with the diaphragm k .

The flexible covering l extends through a flanged annulus, q , and between its flange and that of the socket-piece m , the two flanges being connected by screws r, r, r .

From the flange of the socket-piece m , two tenons, s, s , are extended, in manner as represented in figs. 7 and

8. These tenons are to enter corresponding holes made in the head G, and are to be held in place by pins passed laterally into the head, and into or through holes π , made crosswise in the tenons.

The head G is supported on a dove-tailed slide, H, which rests on a bed-plate, I, and between parallel guides $u' u'$, raised thereon. The steam-chest C is supported on and by standards $v v v$, erected in the said base.

Furthermore, two screws $w w$ are extended from and screwed into the flange of the steam-chest. The heads of these screws, when the mould and die are in conjunction, enter corresponding sockets $x x$, made in the head G, and are held thereto by two bolts $y y$, connected with two levers $z z$, jointed together, and arranged in manner as represented.

With my invention, one head G, with its sectors and their operative screw, as shown in the drawings, and one steam-chest, will suffice for any number of moulds and dies, however these latter may vary in their forms in these parts of them by which a hat while being pressed is shaped. The removal and fixation of any die or mould from the head to the steam-chest, is a matter, the performance of which will consume but little time and labor. The Morse machine requires a separate steam-chest and pressing to every mould and its die, and as the die is fastened to the head by many bolts, it becomes unprofitable and injurious in practice to remove it. For such or other reasons, the mould must be separated from the steam-chest.

The advantages of my improved machine over that of the said Morse may be thus illustrated:

If we suppose a hat-presser or manufacturer of straw goods to receive, as is the common practice, an order for several hundred hats, some of which shall be of one form, and others of various other forms, there being in the lot twelve kinds.

To comply with this order by the machine of Morse, would require the hatter to have twelve of such machines, but to accomplish the order by my invention, but one machine or steam-chest and pressing-mechanism, and twelve moulds, and the dies therefor, would be required, thereby saving the expense of eleven steam-chests, eleven heads and pressing-mechanisms, besides the room which would be taken up by the employment of them.

What, therefore, I claim as my invention, is as follows:

I claim the combination and arrangement of the socket-piece m , the head G, the diaphragm k , the elastic covering l , and flanged ring q of the die, the said socket-piece m and flanged ring q being connected, substantially as described.

And for use with the steam-chest C, when combined with a mould and die, and mechanism for forcing the die into the mould for the purpose of pressing a hat, I claim the combination, substantially as described, for fastening a mould, B, to the mouth of the steam-chest, the same consisting of the flange a , the annulus F, the clamp-ring E, the screws g , the projections c , (of the flange d), and notches f of the said ring, the whole being arranged in manner, and to operate substantially as described.

I claim the combination of the presser or elastic die with the head G, by the tenons s , their pins and holes, the same being so arranged as to enable the said presser or die to be readily removed from the head G, without disturbing the connection of the diaphragm and the elastic covering of the presser.

WILLIAM E. GEORGE.
